BEAD LOOM

Samuel Wallach, New York, N. Y., assignor to
Walco Bead Co., New York, N. Y., a firm

Application May 3, 1935, Serial No. 19,539

7 Claims. (Cl. 139—34)

The invention relates to a bead loom which is adapted to be used to hold a plurality of threads in spaced parallel relation so that beads may be woven by hand thereupon to form beaded belts and other ornamental beaded articles. The manner in which such a loom is used to make the beaded articles is well known and need not be described since the invention herein relates only to the loom.

10 It is an object of the invention to devise a new and novel form of bead loom which provides a more rigid and inexpensive frame for the loom.

Another object is to devise a new and novel method of constructing a bead loom frame from 15 wire in which the joined ends of the wire are concealed by other devices carried by the loom frame.

Other objects of the invention will be more apparent from the following description taken in 20 connection with the accompanying drawing showing the preferred embodiment of the invention, in which:

Figure 1 is a perspective view of the bead loom showing the rigid frame construction.

25 Figure 2 is a view showing one end of the wire frame with a coil of wire being pushed or pulled into position to cover the joined abutting ends of the wire forming the bent rectangular frame.

Bead looms are generally simple devices and 30 consequently it is important that they be inexpensive in order to command the interest of those who make beaded articles by hand. It is desirable that the frame of the bead loom be fairly rigid in order that more effective use of 35 the loom may be had and so that the rolls upon which the warp threads are wound will remain in clamped position and retain the threads taut. A more rigid frame also enables the rolls upon 40 which the spaced warp threads are wound to be more securely supported in position.

The bead loom of the invention comprises a frame formed of a single piece of wire which is sufficiently heavy to provide a rigid frame. The wire is cut off to proper length and bent 45 into the form of an elongated rectangle with the abutting ends of the wire being positioned in one of the ends of the rectangle. Wire coils 10, which may be spring coils, have the wire inserted through their center. These wire coils 10 may 50 be positioned upon the wire prior to its being bent into rectangular form, if desired. It is only important that the coils be placed upon the wire prior to the abutting ends of the wire being secured together. The coils provide a plurality of 55 substantially equally spaced grooves for uni-

formly spacing the warp threads of the loom. Any means, however, is contemplated for providing spaced grooves and such a groove means need not necessarily be carried by the wire forming the end of the rectangular loop.

5 The abutting ends of the single wire are secured together in any desired manner to provide a continuous wire loop for the frame, such as by welding, soldering or any other suitable manner. One of the coils is then pulled or pushed around 10 the corner of the wire rectangle so that it covers the wire forming the end of the rectangle having the abutting ends of the wire. This coil then conceals the joint between the secured ends of the wire. The other coil may have been initially 15 placed in its position upon the other end of the rectangle or rectangular loop prior to bending, or if it is not so positioned before the wire is bent into the rectangular loop, then it too may be pulled or pushed around the corner or bend 20 of the rectangular loop onto the wire forming the end of the rectangle.

The ends of the rectangular loop are bent upwardly and preferably are bent towards each other so that they form angularly disposed ends 25 for the frame. The center portion 13 of the frame forms a base therefor.

The sides 14 of the bent up end portions of the frame preferably have the loops 17 secured thereto in any desired manner, which loops 30 form roll supporting means. These roll supporting means may be secured to any part of the frame so long as they provide a support for a roll adjacent the end of the frame and above 35 the base 13 of the frame.

A roll 18 is carried at each end of the frame and supported by the roll supporting means 17. The rolls preferably carry a pin 19 projecting from each end thereof which are received in the roll supporting loops 17 so as to rotatably support the roll. At least one pin may be threaded in order to carry a wing nut 20 for clamping the rolls 18 in position against rotation. Any roll clamping means is contemplated for holding the rollers against rotation. It will be observed that 40 the frame 13 dispenses with any bracing or spacing means between the ends 14 of the loop forming the frame, other than such bracing or spacing as is furnished by the rolls 18. It should be noted, however, that the rolls are not intended to 45 furnish any such bracing or spacing means, although they would serve this function if it were needed.

In use a plurality of threads are secured to one roll and preferably each thread is positioned in 55

one of the grooves formed by the coil carried upon the end 12 of the rectangular loop. These coils form grooves which position the threads in spaced parallel relation and retain them in this relation.

- 5 The other ends of the threads are secured to the other roll 18 and are adapted to be rolled up thereupon as the beading progresses. It is obvious from the description and drawing that as the beaded article being made upon the loom becomes longer than the space between the ends of the frame 12, the rolls are rotated so that additional thread is unrolled from one roll and the beaded article is rolled upon the other roll. The wing nuts 20 are then tightened to hold the rolls 15 against rotation and the making of the beaded article may then continue.

A new and novel method of tightening the spaced threads is obtained by the bead loom described above. This method involves the pressing together of the ends 12 of the frame 13 prior to anchoring or tightening the second roll against rotation, rotating the untightened roll 18 until the threads are taut and then tightening or anchoring the roller against rotation. Now when the frame is released and springs back to its normal position, the threads are pulled tight and no sag or bow will appear in any of the threads. These tightly pulled threads, without any sag or arc, are easier to weave the beads upon than threads which sag even slightly relatively to the other threads. Any frame which provides sufficient resiliency to obtain this method of obtaining tightly pulled threads or any frame having means separate from the frame is contemplated 30 herein.

Although certain steps have been specified in the manufacture of the bead loom, it is to be understood that the sequence of those steps as stated in this description need not be followed, excepting that it is essential that the coils 10 be placed upon the wire prior to the securing together of the abutting ends of the wire. A new and novel method of manufacturing a bead loom has also been described herein by which the abutting ends 45 of the wire forming the continuous looped frame is concealed within one of the coils 10 forming the thread grooves. As pointed out above, the sequence of steps in the making of the bead loom is not important excepting in the particular 50 pointed out above.

Various modifications will occur to those skilled in the art in the configuration, composition and disposition of the component elements going to make up the invention as a whole, as well as in the selective combination or application of the respective elements, and no limitation is intended by the phraseology of the foregoing description or illustrations in the accompanying drawing.

What is claimed is:

- 60 1. A bead loom comprising a resilient frame constructed from a single wire with its ends joined to provide a continuous wire frame and having the form of a rectangular wire loop with the ends thereof bent upwardly, the resilient wire providing the major resiliency for the frame in the base wires and lesser resiliency in the bent-up ends and at the bends, a series of grooves carried by the upwardly extending ends of the rectangular loop of the frame, and a roll rotatably supported 65 upon the sides of each upwardly bent end of the loop, the rolls providing the sole transverse spacing and bracing means between the ends of the wire loop.
- 70 2. A bead loom comprising a resilient frame constructed from a single wire with its ends joined

to provide a continuous wire frame and having the form of a rectangular wire loop with the ends thereof bent upwardly, the center portion forming a base for the frame, the resilient wire providing the major resiliency for the frame in the base wires and lesser resiliency in the bent-up ends and at the bends, a wire coil carried upon each of the wires forming the end of the rectangular wire loop and forming spaced grooves, roll supporting means carried by the frame to 10 support a pair of rolls above the base of the frame, a pair of rolls carried by the supporting means, the rolls providing the sole transverse spacing and bracing means between the ends of the wire loop, and means to secure each roll 15 against rotation.

3. A bead loom comprising a resilient frame constructed from a single wire with its ends joined to provide a continuous wire frame and having the form of a rectangular wire loop with the ends thereof bent upwardly and tilted at an angle towards each other, the center portion forming a base for the frame, the resilient wire providing the major resiliency for the frame in the base wires and lesser resiliency in the bent-up ends 20 and at the bends, spaced grooves carried upon each of the upwardly extending ends of the frame, roll supporting means carried by the frame to support a pair of rolls above the base of the frame, a pair of rolls supported upon the roll supporting means, the rolls providing the sole transverse spacing and bracing means between the ends of the wire loop, and means to secure each roll 25 against rotation.

4. A bead loom comprising a resilient frame 30 having the form of a rectangular wire loop with the ends thereof bent upwardly and tilted at an angle towards each other, the center portion forming a base for the frame, the resilient wire providing the major resiliency for the frame in the base wires and lesser resiliency in the bent-up ends and at the bends, the ends of the wire being joined in one of the ends of the wire loop to form a continuous wire loop, a wire coil carried upon each of the upwardly extending ends of 45 the rectangular wire loop and forming spaced grooves, roll supporting means carried by the frame to support a pair of rolls above the base of the frame, a roll supported upon each roll supporting means, and means to secure each roll 50 against rotation.

5. A bead loom comprising a resilient frame constructed from a single wire with its ends joined to provide a continuous wire frame and having the form of a rectangular wire loop with the ends thereof bent upwardly, the resilient wire providing the major resiliency for the frame in the base wires and lesser resiliency in the bent-up ends and at the bends, a wire coil carried upon each of the upwardly extending ends of the rectangular wire loop and forming spaced grooves, a roll supporting means secured to each side of the upwardly extending ends of the rectangular loop of the frame, a roll supported upon each roll supporting means, the rolls providing the sole 60 transverse spacing and bracing means between the ends of the wire loop, and means to secure each roll against rotation.

6. A bead loom comprising a resilient frame constructed from a single wire with its ends joined 70 to provide a continuous wire frame and having the form of a rectangular wire loop with the ends thereof bent upwardly, the resilient wire providing the major resiliency for the frame in the base wires and lesser resiliency in the bent- 75

- up ends and at the bends, the ends of the wire being joined in one of the ends of the wire loop, a wire coil carried upon each of the upwardly extending ends of the rectangular wire loop and forming spaced grooves, a roll supporting means secured to each side of the upwardly extending ends of the rectangular loop of the frame, a roll supported upon each roll supporting means, and means to secure each roll against rotation.
- 5 7. A bead loom comprising a resilient frame having the form of a rectangular wire loop with the ends thereof bent upwardly and tilted at an angle towards each other, the resilient wire pro-
- viding the major resiliency for the frame in the base wires and lesser resiliency in the bent-up ends and at the bends, the ends of the wire being joined in one of the ends of the wire loop, a wire coil carried upon each of the upwardly extending ends of the rectangular wire loop and forming spaced grooves, a roll supporting loop formed from bent wire and secured to each side of the upwardly extending ends of the rectangular loop of the frame, a roll supported upon each roll supporting loop, and means to secure each roll against rotation.
